Primary Examiner — David G Muller*Assistant Examiner* — Nathan M Johnston*(74) Attorney, Agent, or Firm* — Calfee, Halter & Griswold, LLP(57) **CLAIM**

I claim the ornamental design for a mirror, as shown and described.

DESCRIPTION

FIG. 1 is a front elevational view of a mirror;

FIG. 2 is a rear elevational view thereof;

FIG. 3 is a right side elevational view thereof; and,

FIG. 4 is a top plan view thereof.

The broken lines form no part of the claimed design.
